UNITED STATES PATENT OFFICE.

NEWMAN H. HOLLAND, OF WEST ORANGE, NEW JERSEY, ASSIGNOR TO NEW JERSEY PATENT COMPANY, OF WEST ORANGE, NEW JERSEY, A CORPORATION OF NEW JERSEY.

PHONOGRAPH RECORDER.

Application filed November 6, 1920. Serial No. 422,122.

To all whom it may concern:

Be it known that I, NEWMAN H. HOLLAND, a subject of the King of Great Britain, and a resident of West Orange, in the county of 5 Essex and State of New Jersey, have invented certain new and useful Improvements in Phonograph Recorders, of which the following is a description.

My invention relates to phonograph recorders and more particularly phonograph recorders of the floating-weight type.

It is highly essential in phonograph recorders in order to obtain a faithful record of the matter to be recorded, for the construction and arrangement to be such that the recording stylus will engage the record tablet with a pressure not appreciably greater or less than a certain predetermined amount. There are certain advantages which would 15 obviously result from the use of a recorder of the floating-weight type, such as rendering it possible during the recording operation to support the diaphragm or vibratory means against movement towards and away 20 from the record tablet, and, especially in the case of an electro-magnet recorder, to maintain the diaphragm or vibratory means in fixed relation to the means, such as the electro-magnet, for effecting vibration thereof. Constructions heretofore suggested for 25 phonograph recorders of the floating-weight type are impracticable, for in these constructions during the recording operation there is either insufficient tension in the connection between the stylus and the diaphragm to prevent looseness and rattling in such connection, or the pressure with which the stylus engages the record tablet is far 30 too great.

One of the principal objects of my invention is to provide an improved construction for phonograph recorders of the floating-weight type wherein during the recording operation the tension in the connection between the stylus and the diaphragm or vibratory means is sufficient to prevent lost 45 motion and rattling, and at the same time the recording stylus engages the record tablet with the proper pressure.

Another object of my invention resides in the provision of a floating-weight recorder of this character wherein the vibrations imparted to the recording stylus correspond in amplitude to the vibrations of 50 the central portion of the diaphragm.

Other objects and features of my invention will be hereinafter more specifically described and claimed.

In order that my invention may be more clearly understood, attention is directed to the drawing accompanying and forming a part of this specification and in which the single figure is a fragmental view in elevation, partly in section, of a phonograph illustrating one form of recorder embodying 60 my invention, in operative position with respect to the record tablet.

Referring to the drawing, reference character 1 represents a cylindrical record tablet such as is usually employed on business 70 phonographs or dictating machines, and 2 the traveling arm or carriage which in the operation of the phonograph is fed rectilinearly across the tablet 1. The carriage 2 constitutes a support for the sound box 75 casing 3 of the recorder, being provided with an opening in which said casing is removably secured in any suitable manner. A metallic diaphragm 4 is suitably secured as by means of a ring 5 within the casing 80 3 so as to close the open end of the latter. In the form of recorder shown, the diaphragm 4 is adapted to be vibrated by means of an electro-magnet 6 suitably mounted in a fixed position within the casing 3 and 85 the terminals of which are respectively connected to binding posts 7 and 8, the latter extending through and being insulated from the upper end wall of the casing 3. The binding posts 7 and 8 are adapted to be 90 electrically connected to a telephonic transmitter, not shown.

Reference character 9 represents a floating-weight preferably having one end pivotally supported at 10 between a pair of 95 lugs 11, only one of which is shown, projecting downwardly from the sound box casing 3, and provided at its other end with a pin 12 which is embraced by a keeper 13 secured to the sound box casing 100 3 and extending downwardly therefrom at a point diametrically opposite the lugs 11. A stylus lever 14 is pivotally mounted intermediate its ends at 15 on the floating-weight 9 within an opening 16 provided in the latter. The stylus lever 14 has a recording stylus 17 mounted in one end thereof and its other end is connected as by means of a link 18 with a button 19 fixed 105 to the diaphragm 4.

The arms of the stylus lever 14 are of unequal length, the shorter arm being connected, as by means of the link 18 and button 19, to the diaphragm 4 and the longer arm carrying the stylus 17. It will, therefore, be apparent that the tension in the connection between the diaphragm 4 and the lever 14 will be greater than if the lever were pivoted midway between its ends as is customary, and greater than the pressure with which the stylus 17 engages the record tablet 1. This tension in the connection between the stylus lever and the diaphragm, and the pressure with which the stylus engages the record tablet, will be dependent on the mass of the floating-weight 9, the point where the stylus lever 14 is pivoted on the floating-weight, and the relative lengths of the two arms of the stylus lever. In the construction shown the longer arm of the stylus lever 14 is substantially twice the length of the shorter arm and, therefore, the tension in the connection, which includes link 18, between the diaphragm and the stylus lever 14, will be equal to substantially twice the pressure with which the stylus 17 engages the tablet 1. The mass of the floating-weight 9 and the point 15 thereon at which the lever 14 is pivotally mounted, are so chosen that the stylus 17 engages the tablet 1, when the recorder is in operative position as shown, with exactly the proper degree of pressure to properly record on the tablet. Under these conditions it is found that the tension in the connection between the diaphragm and the stylus lever is entirely sufficient to prevent all looseness, rattling, etc. in such connection during the recording operation, with the result that a faithful record is produced.

It is also important while obtaining the results just described, to impart to the recording stylus vibrations corresponding in amplitude to the vibrations of the diaphragm at the center thereof. This I accomplish by connecting the shorter arm of the stylus lever 14 to the diaphragm 4 eccentrically thereof, as by means of link 18 and button 19, so that the distance between the center of the diaphragm and the point at which the stylus lever is connected thereto and the radius of the diaphragm, are in the same ratio as the lengths of the arms of lever 14. Thus where the shorter arm of the lever 14 is one-half the length of the longer arm thereof, as shown, the shorter arm of the lever is connected to the diaphragm at a point midway between the center and the edge thereof.

It is to be understood that in the embodiment illustrated, the mass of the floating-

weight, the point on the floating weight at which the stylus lever is pivoted, the relative lengths of the arms of the stylus lever and the point at which the diaphragm is connected to the stylus lever are subject to wide variation, and that many other modifications may be made in the form and arrangement of the parts without departure from the spirit of my invention and the scope of the appended claims.

Having now described my invention, what I claim as new and desire to protect by Letters Patent, is as follows:

1. A phonograph recorder comprising a diaphragm, a member movable relative thereto, a stylus lever pivotally mounted intermediate its ends on said member and having arms of unequal length, the shorter arm of said lever being connected to said diaphragm eccentrically thereof, and a stylus carried by the longer arm of said lever, substantially as described.

2. A phonograph recorder comprising a diaphragm, a stylus lever pivotally mounted intermediate its ends and having arms of unequal length, the pivot on which said lever is mounted being movable relative to the diaphragm, the shorter arm of said lever being connected to said diaphragm eccentrically thereof, and a stylus carried by the longer arm of said lever, the distance between the center of the diaphragm and the point thereof to which the stylus lever is connected and the length of the radius of the diaphragm being in substantially the same ratio as the length of the shorter arm of the stylus lever and the length of the longer arm thereof, substantially as described.

3. A phonograph recorder comprising a diaphragm, a stylus lever pivotally mounted intermediate its ends and having arms of unequal length, the pivot on which said lever is mounted being movable relative to the diaphragm, the shorter arm of said lever being substantially half the length of the longer arm thereof and being connected to the diaphragm at a point substantially midway between the center and the edge thereof, and a stylus carried by the longer arm of said lever, substantially as described.

4. A phonograph recorder comprising a diaphragm, a stylus lever pivotally mounted intermediate its ends and having arms of unequal length, the shorter arm of said lever being connected to said diaphragm eccentrically thereof, and a stylus carried by the longer arm of said lever, substantially as described.

This specification signed this third day of November, 1920.

NEWMAN H. HOLLAND.
